UNITED STATES PATENT OFFICE.

EDOUARD BENEDICTUS, OF PARIS, FRANCE.

PRESS-PLATE.

1,206,656.

Specification of Letters Patent. Patented Nov. 28, 1916.

Application filed August 1, 1912. Serial No. 712,732.

To all whom it may concern:

Be it known that I, EDOUARD BENEDICTUS, a resident of 25 Rue Fourcroy, at Paris, France, and a citizen of the Republic of France, have invented certain new and useful Improvements in Press-Plates, of which the following is a specification.

This invention has for an object plates for presses more particularly intended for the manufacture of glass strengthened or reinforced by the interposition between two sheets of glass, of sheets of celluloid, gelatin, celluloid and gelatin or other similar materials by the processes described in the specifications of patent applications Benedictus, Serial Numbers 537,557 filed January 11th, 1910, 632,850 filed June 13th 1911, 633,123 filed June 14th 1911.

The invention consists in imparting to these plates or to one of them only, a shape slightly dished or convex so as to insure compression of the material extending progressively from the center to the periphery and thus to cause as completely as possible an expulsion of the liquids or fluids retained by the materials subjected to compression.

The invention consists moreover in furnishing the plates of the press with a mattress or cushioning device composed of a sufficiently thick layer of an elastic or compressible material such as cork, felt, caoutchouc, paper, etc., with a view to transmitting and at the same time moderating or cushioning the forces of compression from the dished or convex face of the plate to the plane surface of the glass and to prevent the breakage of the latter, when manufacture of strengthened glass according to the above processes is taking place.

In the manufacture of glass of which the interposed material is of less dimensions than those of the glass sheets, so that a marginal space is left at the periphery of the glass, it is expedient, in order to prevent breakage of the glass sheets at their edges, to determine in a precise manner the dimensions of the mattress made of elastic material. The dimensions of this mattress must be less than those of the glass sheets to be compressed and such that at the end of the compressing action they attain by their lateral expansion substantially to those of the interposed material between the glass sheets. Failing this precaution, in effect, the sheets

of glass which project beyond the interposed material between the glass sheets, would be subjected to unsupported marginal strains, and would break.

Instead of employing plates of unvarying convex shape I may employ deformable plates of which the exterior face bends or yields in such a way that it can pass from the plane form to the convex form and inversely. These plates are composed preferably of a thick unyielding portion comprising a conduit or passage allowing a fluid under pressure to escape, the exterior face of this thick part being covered by a sheet of metal or other flexible material, fixed in a fluid-tight manner at its periphery. The elasticity of the metal is sufficient to enable me to obtain bends or curvatures some millimeters deep, such as those generally necessary in practice.

The advantage of this arrangement consists in that it permits at the beginning of the operation to commence the application of pressure from the center, then to increase it progressively to the periphery so as to insure the complete expulsion of the liquid and to allow of exerting at the finish a uniform pressure over the whole surface of the glass or other body submitted to pressure.

To obtain the dishing or curving of the flexible face of the plate, I may inject any fluid whatever (liquid, steam or gas) under pressure; I may also make use of this fluid for the heating of the plate.

The plates may be furnished with cork or other elastic or compressible material as has been above stated.

In the accompanying drawings, Figure 1 is a vertical section through press plates in which my invention is illustrated in one form; Fig. 2 is a similar view of the same under pressure; Figs. 3 and 4 are views corresponding to Figs. 1 and 2 but illustrating the invention applied in a different manner.

Referring to Figs. 1 and 2, the upper press plate *a* carries on its convexed lower face a mattress of elastic material *b*, such as cork, felt, rubber or other suitable material. The face of the lower press plate *a*, which is flat, is similarly furnished with a mattress *b* identical with *a*. As will be readily understood, the sheet *d* of gelatin, which is confined between the sheets *c* and *c'* of glass, is subjected to pressure, first at a point beneath

the crown of the press plate *a*, while the pressure gradually spreads throughout the entire width of the mattress *b* as the latter is compressed by the downward movement 5 of the plate.

In Figs. 3 and 4 the upper press plate *e* is hollow and its face comprises a flexible sheet *e*¹ which may be rendered convex by the introduction of fluid through the passage *f* 10 in the shaft of the press. The lower press plate *e*² is solid and flat and the other elements of the illustration are likewise the same as in these Figs. 1 and 2. The operation of this press differs from that shown 15 in Figs. 1 and 2, only in that here the face of the plate itself as well as the cushioning mattress flattens out under the action of the press.

What I claim and desire to secure by Letters Patent of the United States is:

1. A press of the character described having upper and lower press plates, one of said plates having its face normally convexed, in combination with cushioning mattresses on 20 the faces of said plates, said mattresses being susceptible of material lateral expansion in all directions under pressure, for the purpose described.

2. A press of the character described, having upper and lower press plates, one of the 30 said plates having its face permanently convexed, in combination with cushioning mattresses on the faces of said plates, for the purpose described.

3. A press for compressing sheets of glass 35 upon an interposed sheet of adhesive, said press having upper and lower press plates, one of said plates having its face normally convexed, in combination with cushioning mattresses on the faces of said plates, said 40 mattresses being normally of less area than that of the adhesive sheet but expanding under operating pressure to substantially the area of the adhesive sheet, for the purpose described.

In testimony whereof I have signed my name to this specification, in the presence of two subscribing witnesses.

EDOUARD BENEDICTUS.

Witnesses:

FERNAND SWANK,
LEON PEITTER.
